CLAIM

The ornamental design for a organizing insert for storage case, as shown.

DESCRIPTION

FIG. 1 is a left, front, top perspective view of the organizing insert for storage case;

FIG. 2 is a right, front, bottom perspective view of the organizing insert for storage case;

FIG. 3 is a right elevation view of the organizing insert for storage case;

FIG. 4 is a left elevation view of the organizing insert for storage case;

FIG. 5 is a front elevation view of the organizing insert for storage case;

FIG. 6 is a rear elevation view of the organizing insert for storage case;

FIG. 7 is a top view of the organizing insert for storage case;

FIG. 8 is a bottom view of the organizing insert for storage case;

FIG. 9 is a right, rear, top perspective view of the organizing insert for storage case as used within a storage case;

FIG. 10 is another right, rear, top perspective view of the organizing insert for storage case as used within a storage case; and,

FIG. 11 is a left, rear, top perspective view of the organizing insert for storage case seated atop another organizing insert. The broken lines showing portions of the design in all figures are included for the purpose of illustrating environment and do not form a part of the claimed design.

1 Claim, 8 Drawing Sheets
